BOBBIN HANDLING ARRANGEMENT

Charles A. Wethington, Spartanburg, S.C., assignor to Deering Milliken Research Corporation, Spartanburg, S.C., a corporation of Delaware

Filed Oct. 6, 1961, Ser. No. 143,421

7 Claims. (Cl. 209—85)

This invention relates to a transfer arrangement, and more particularly to a bobbin handling arrangement for transferring bobbins, quills, or the like from a common supply means to a plurality of user stations.

In recent years there have been several proposals for automating the doffing and donning of textile processing machines, such as spinning frames. In order to more fully automate such doffing and donning, it is desirable to have a mechanized bobbin transfer arrangement for transferring bobbins from a central source to a plurality of user stations, such as loading stations for loading the supply bobbins onto the doffing and donning apparatus. It is an object of this invention to provide an improved and simplified bobbin transfer arrangement which is particularly adapted for supplying bobbins to a plurality of user stations which may be disposed at mechanical doffer loading stations for mechanized loading of automatic or semi-automatic doffing and donning apparatus.

A further feature of the invention is the provision of a bobbin transfer arrangement which includes simple and efficient means for removing defective bobbins, and more particularly bobbins which are of shorter length than is desired at the user stations.

Still other objects, features and attendant advantages will become apparent to those skilled in the art from a reading of the following detailed description of one preferred embodiment of the invention, taken in conjunction with the accompanying drawings wherein:

FIGURE 1 is a schematic illustration in perspective of one physical embodiment constructed according to the invention.

FIGURE 2 is a schematic line drawing in side elevation of the arrangement of FIGURE 1.

FIGURE 3 is a fragmentary view of one portion of the adjustable guide and support frame arrangement for the pocketed conveyor portion of the arrangement.

FIGURE 4 is a fragmentary view in partial section illustrating in more detail the bobbin discharge station gate construction and operation.

FIGURE 5 is a bottom view of the bobbin discharge station, omitting the bobbin discharge gate therefor for purposes of clarity of illustration.

FIGURE 6 is a fragmentary schematic illustration is perspective as viewed from the bottom and side of the defective bobbin removal arrangement in the bobbin transfer arrangement in FIGURES 1 and 2.

FIGURE 7 is a bottom view of the defective bobbin removal arrangement of FIGURE 6.

Referring now in detail to the figures of the drawings, bobbins, quills, or the like, B, are delivered from a common supply source, such as a hopper or bin 11 as by a shaker 15 extending through a door 13 formed in a side wall of the bin, the bobbins or quills being delivered to a first narrow width (approximately two to four or so bobbin diameters) conveyor in the form of a continuous belt 17, from which they proceed longitudinally to a second transversely extending wider width conveyor 19 (slightly greater in width than the length of the bobbins to be conveyed), which may also be in the form of a continuous belt. Belt conveyors 17 and 19 may be suitably driven through the medium of a drive motor 23 and suitable intermediate mechanical connections, such as gearing, pulleys and drive belts, generally indicated at 25 and 27.

2

The bobbins are delivered from the belt 19, which is downwardly and forwardly inclined, onto a pocketed conveyor 21, in the form of a continuous belt having slats 21f fixed at spaced intervals transversely across its surface along the entire length thereof, to form pockets 21g of suitable width and depth to receive a single bobbin B in each pocket. The bobbins are loaded onto the conveyor 21 along a first upwardly inclined run 21a thereof, and are then transported along this run 21a, through a second horizontal run 21b and then along a reverse horizontal run 21c, past a plurality of user stations 59. Such bobbins as are not discharged at or prior to reaching the user stations are returned along a return run 21d and continue again in the same path to and past the loading zone adjacent transverse belt conveyor 19 and thence again to the user station positions 59.

In order to provide bobbins at the user stations 59 in a suitable and desired oriented manner, that is with their head and base ends all extending respectively in the same directions and in essentially parallel relation, it is desirable to provide a bobbin reorienting device for removing and reorienting any bobbins which are delivered onto the pocketed conveyor 21 with their head or base ends extending in the wrong direction. This may be effected through the medium of a compressed air jet nozzle, generally indicated and shown schematically at 20 in FIGURE 1, adjacent the run 21a of the conveyor 21 and with its discharge orifice disposed so as to catch the large diameter base ends of the bobbins passing there-adjacent, but to miss the smaller diameter head of the bobbins, whereby bobbins having their large base ends extending toward the side on which the nozzle 20 is mounted will be kicked off the run 21a by the stream of air proceeding from air nozzle 20 and reversed in mid-air and subsequently fall onto conveyor 17 in reversed form. From the conveyor 17 the bobbins are then retransported in longitudinally extending relation to the conveyor 19 and delivered to the run 21a in properly transversely oriented manner. This general bobbin conveying and reorienting arrangement 11-20 is only schematically and generally illustrated herein, such having been previously disclosed and described in detail in the prior copending application of Robert M. Ingham, Jr., Serial Number 767,012, now Patent No. 3,031,059, to which reference may be made for further details of construction and operation.

The pocketed conveyor 21 is suitably supported as by guide rolls 31, 33 and 35, carried as by a frame generally indicated at 55, the rolls 33 and 35 being idler rolls, and roll 31 being a drive roll which may be suitably driven as by a drive motor 29 and mechanical connection 30. In operation, each of motors 23 and 29 may run continuously.

The pocketed conveyor 21 is further guided along its runs 21c and 21d through the medium of a bobbin and belt guiding and supporting apron 37 which is preferably driven solely by contact thereof with the conveyor 21 and such bobbins as are remaining thereon during the passage of the conveyor 21 in contact with the apron 37. Apron 37 is guided through the medium of a plurality of guide rolls 39-53 suitably mounted as on support frame 55, there being preferably provided three guide rolls 41, 43 and 45 in the zone of external bend of conveyor belt 21 at the intersection or runs 21c and 21d. The apron 37 may be maintained under a desired substantially taut condition, as through the medium of idler rolls 51 and 53, with one or both of these rolls being resiliently biased away from the other as through the medium of a tension spring (not shown).

Apron 37 serves the dual functions of smooth guiding and supporting of the conveyor 21 and such bobbins as are contained thereon along the latter part of the run 21c

and the major part of run 21d as well as the zone of external bend of the conveyor 21 at the intersection of the two runs 21c and 21b, and of aiding in maintaining the conveyor 21 in clean condition. This cleaning function is achieved through the slightly differential speed at which the idler apron is driven by its frictional contact with the conveyor 21, such being effected as a result of frictional drag on the apron 37 and idler rolls 39-53 at the various support points therefor. The apron 37 thus provides a unique and simple solution for the problem of effecting an external bend in the pocketed conveyor, without catching the slats 21f on the guide in the zone of external bend, while along aiding in maintaining the cleanliness of the conveyor 21.

Conveyor 21 is further guided along the curved connecting portion between runs 21b and 21c and further along run 21c through the medium of a guide and support plate arrangement 55b, 55c which forms a part of the overall guide and support frame 55 for the pocketed conveyor 21. This guide plate arrangement takes the form of a curved end guide plate 55b and a longitudinally extending horizontally disposed straight guide plate 55c for the lower discharge run 21c, as shown more particularly in FIGURES 1 and 3. Referring now to FIGURES 1-3, the entire pocketed conveyor 21 is enclosed on opposite lateral sides thereof by opposite side walls 55a of support frame 55 which serve to prevent undesired falling off of the bobbins from the lateral sides of the conveyor 21.

The support frame 55 also includes in the zone of guide plates 55b and 55c a bottom support wall in the form of inverted U-channel member 55d to which is secured to straight guide plate 55c, as by screws 55f which are threadedly received in but do not extend above the upper guide surface of the bottom guide plate 55c (see FIGURE 4). In order to provide for adjustment of the guide roll 31 to take up any slack resulting from stretching of the belt conveyor 21, as after extended use thereof, the motor 29 and shaft 31 as well as drive roll 31, are disposed for sliding movement substantially horizontally and the end guide plate 55b is likewise horizontally slidably adjustable. To this end, the guide plate 55b includes a bottom tongue 55b' which is adjustably secured to the channel member 55d, as through the medium of threaded studs 55bs welded or soldered onto the tongue 55b' and wing nuts 55d, the nuts 55bs being disposed beneath the U-channel 55d and the studs 55bs extending through longitudinal adjustment slots 55d' formed in the U-channel member 55d. The guide plate 55c includes two side extensions 55c'' which extend beside the tongue 55b', the overlapping of these two guide plates 55b and 55c thus providing a substantially continuous guide surface 55b, 55c for conveyor 21 in the adjustment zone.

It will be noted that all of the connections for securing the guide plates 55b and 55c to the support channel member 55b extend through the channel member 55d and into the plates 55b and 55c, with only flush or recessed connections therebetween on the upper surface of the members 55b and 55c, as for instance studs 55bs and screws 55f. This assures that the conveyor 21 and its surface slats 21f will be slidably guided without hanging up on any surface protrusions formed on the guide surfaces of members 55b and 55c. Further, in order to assure that the intersection between the curved end guide plate 55b and the straight horizontal plate 55c does not cause hanging up of the slats or bobbins which may ride therewith, the opposing end faces of the tongue 55b' and the cut out portion of the guide plate 55c are beveled, to permit sliding of bobbins therefrom and thereonto without hanging up. This beveling is particularly advantageous in the event that short bobbins should ride through this area.

A further curved guide plate 56, suitably secured to and forming a part of the support frame 55, serves to guide and support the bobbins along the curved connecting portion of conveyor 21 between runs 21d and 21a.

In order to remove defective bobbins in the form of

bobbins which are undesirably short, as for instance broken bobbins or short unbroken bobbins, a short bobbin removal station, generally indicated at 61 is provided. This short bobbin removal station takes the form of an opening 61a cut in the bottom of each of guide plates 55c and U-channel 55d. This opening 61a is of such width as to permit the falling by gravity of bobbins which are shorter than a selected standard length, while permitting the supported passage thereby of bobbins of the selected length. In order to assure that the bobbins are properly aligned as they pass over the opening 61a, so that any laterally displaced standard size bobbins will not fall through the opening 61a, there is provided a lateral cam guide 69 adjacent one lateral wall 55a with its beginning point in advance of the opening 61a. It is desirable that this cam guide 69 be disposed on the side of the conveyor at which the base ends of the bobbins are disposed, it having been found that the smaller ends of short bobbins more easily fall through the opening 61a than the larger ends of the bobbins. The cam guide 69 has its main lateral edge spaced from the adjacent side of the opening 61a, and is spaced a distance from the opposite side wall 55a such that there is only a small clearance between the opposite side wall and a bobbin of standard length passing therebetween. Thus, standard length bobbins are conveyed by the slats 21f on the conveyor 21 past the opening 61a, while those bobbins which are shorter than standard size will drop through the extended opening 61a, which preferably covers a distance of several bobbins pocket widths 21g in order to allow ample time for falling of short bobbins therethrough, as shown more clearly in FIGURES 6 and 7. In FIGURE 7 short bobbins B are illustrated as disposed with at least one end hanging free in such manner as to permit falling thereof through the opening 61a as shown in FIGURE 6. As shown in FIGURE 4, the slats 21f do not extend all the way across the width of conveyor 21 to the side wall 59a, but preferably have an open space at each lateral end thereof adjacent the respective side wall 59a, and thereby are free to pass beside the cam guide 69 without interference.

Any desired number of bobbin discharge user stations 59 may be disposed beneath the run 21c of the conveyor 21, dependent, of course, upon the supply rate of the belt conveyor system, and the user rate of the stations 59. In the illustrated embodiment there are three user stations 59 shown, and in FIGURE 4 such a user discharge station 59 is shown in more detail. Each user discharge station 59 includes an opening 59a formed in the guide plate 55c and U-channel member 55d, this opening 59a extending across the width of members 55b and 55c and being selectively closed and opened by a gate generally indicated at 63. Gate 63 may be swingably mounted as by securing on a pivot shaft 63a supported in a pivot mounting 63b which may be secured to the support frame 55. When the gate 63 is in down or open position the bobbins B fall through the opening 59a into a suitable receptacle, as into or through a chute 65, which may have front and rear walls 65a, 65b and side walls 65c for guiding the bobbins received thereby to a suitable side-by-side aligned transversely extending user position.

Since the bobbins B are pushed along with their trailing surface substantially flat against the respective pushing slot 21f, it will be apparent that the center line of the bobbin B at the larger end would normally reach the leading edge of the hole 59 before the smaller diameter end of the bobbin B, and because of this, it is desirable to add an extension 59b to the leading edge of the gate opening 59a to effectively delay the time at which the large end of the bobbin has its center line pass over the effective leading edge formed by the extension 59b, and thus substantially synchronize the time at which the center line of the two ends of the bobbin reach the effective leading edge of the opening 59a. The thickness of the extension 59b should be approximately equal to one-half of the difference between the diameters of the bobbin at its large

and small end. It will be noted that the effect of adding this extension 59b is to further reduce the clearance between the large end of the bobbin and the opposite or trailing edge of the opening 59a. In order to provide substantially the same clearance between the bobbin and the effective leading and trailing edges of the opening 59a at both the large and small end sides of the opening it is desirable to add a further extension 59c on the trailing edge of the opening 59a. This extension 59c should be approximately one and one-half times the difference between the large and small diameter ends of the bobbin. While it is possible to provide a suitable opening with the extensions 59b and 59c as illustrated in FIGURE 5, it will be apparent that this opening 59a might also be formed with the same effect by tapering the leading and trailing edges from the respective extension surface on each respective edge to the opposite end of this edge, rather than having abrupt extensions 59b and 59c as shown. The effect is substantially the same, being that of delaying the passage of the center line of the large end of the bobbin until the center line of the small end of the bobbin reaches the leading edge of the opening 59a, as well as evening of the clearance across the length of the bobbin.

In order to more fully guide the bobbins B during their descent from the opening 55a through the chute 65, the front and rear walls 65a and 65b extend in part to a position closely adjacent the bottom of the U-channel 55d. In order to accommodate this extension of the front and rear walls 65a, 65b of the chute 65, the gate 63 is preferably formed in two split sections 63c, 63d as shown more particularly in broken line open position of the gate in FIGURE 4. This split formation of the gate 63 into two sections thus permits free pivotal movement of the gate without interference with the two upward extensions of the front and rear walls 65a, 65b of the tube 65 while enabling the provision of substantially full guiding of the bobbin into the chute 65 by the upward central extensions of the front and rear walls 65a, 65b. The gate 63 may be suitably selectively pivoted to closed or opened position by any suitable mechanism, such as an electro-mechanical control generally indicated at 67. An actuating element 67 might take the form of a rotary action solenoid or other suitable electro-mechanical or mechanical actuator. It will of course be understood that it is desirable that the control 67 not be actuated to return the gate 63 to closed position during the dropping of a bobbin through the opening, or the partial approach of a bobbin into the opening 59a.

In operation the hopper 11 is provided with a desired supply of bobbins, which are fed through the door 13 by shaker floor 15 onto lateral conveyor 17. The conveyor 17 being of a width corresponding to approximately one or two to four or so bobbin diameters, thus conveys the bobbins longitudinally onto the conveyor 19 in a manner such that they extend substantially transversely on the conveyor 19 and in the feeding trough area formed at the lower end of conveyor 19 in the zone of adjacency of conveyors 19 and 21. The conveyor 21 thus picks up in the pockets 21g succeeding bobbins B, and air jet nozzle 20 reorients onto conveyor 17 standard size bobbins having the base end thereof extending toward the air jet nozzle. The bobbins are then conveyed along the runs 21a and 21b of conveyor 21 and are then guided around the curved end of the conveyor and along the lower run 21c thereof through the medium of guide plates 25b and 25c.

The bobbins are guided into a desired lateral position in advance of the defective bobbin discharge station 61 through the medium of guide cam 69, and short bobbins fall through the opening 61a at the defective short bobbin discharge station 61 as into a suitable receptacle 62, as shown in FIGURE 6. Standard sized bobbins are supported at both ends by the guide plate 55c in the zone of opening 61a and are conveyed therewith to the user discharge station 59.

At the user discharge stations 59 the bobbins may be

discharged through openings 59a under the influence of gravity, through the swinging open of any selected one or more of the gates 63 to the downward or opened position, as shown in broken lines in FIGURE 4. Upon the supplying of the desired quantity of bobbins to a given user station 59 the respective gate 63 is again closed by swinging such to the upper closed position as shown in full lines in FIGURE 4, and subsequent bobbins will pass this station to subsequent stations 59 for discharge, if the gates at such stations are open, or the retained bobbins will be returned to the loading zone along run 21d and again be carried to run 21a for subsequent discharge at one of the user stations 59. The bobbins which are supplied to the loading zone at the intersection of conveyors 19 and 21 will fall into such pockets 21g as remain open, the pockets 21g, however, being formed with a depth and width preferably only slightly more than one bobbin diameter, so as to prevent the catching of more than one bobbin at a time in a given pocket 21g. In order to prevent over supply of bobbins to the loading zone at the intersection of conveyor 19 and conveyor 21 a suitable feedback responsive control may be provided for controlling the shaker floor 15 as a function of the supply of bobbins in the zone between the conveyor 19 and conveyor 21, or the shaker may be manually controlled, if desired, as will readily be apparent to those skilled in the art.

While the invention has been described with respect to only one specific preferred physical embodiment thereof, it will be apparent to those skilled in the art that various modifications and improvements may be made without departing from the scope and spirit of the invention. Accordingly, it will be understood that the invention is not to be limited by the particular illustrative embodiment disclosed and described herein, but only by the scope of the appended claims.

That which is claimed is:

1. A transfer arrangement for bobbins, quills, or the like, comprising a flexible endless band having pockets formed in its outer surface for receiving and holding bobbins, quills or the like, spaced means supporting said band at spaced apart positions to form at least two runs of said band, one of said runs being below another of said runs, and band-and-bobbin-guiding means disposed between said spaced means and below and adjacent the outer pocketed face of said one run, said band-and-bobbin-guiding means having at least one bobbin-discharge opening formed therein for discharge of bobbins from said pockets on said band, defective-bobbin-removal means in advance flow relation to said bobbin-discharge opening for effecting removal of defective bobbins from said band before such bobbins reach said discharge opening, said defective-bobbin-removal means including a short-bobbin-discharge opening formed in said band-and-bobbin-discharge opening formed in said band-and-bobbin-guiding means, said short-bobbin-discharge opening being shorter than said first mentioned discharge opening in the direction of bobbin lengthwise orientation, said pockets extending with their greater length crosswise of said band to align said bobbins, quills, or the like, with their lengths extending crosswise of said band, and end guide means for aligning the longitudinal ends of said bobbins on said band in advance of movement of said bobbins past said short-bobbin-discharge opening to aid in short bobbin detection and discharge at said short-bobbin-discharge opening.

2. A transfer arrangement for bobbins, quills, or the like, comprising a flexible endless band having pockets formed in its outer surface for receiving and holding bobbins, quills, or the like, spaced means supporting said band at spaced apart positions to form at least two runs of said band, one of said runs being below another of said runs, and band-and-bobbin-guiding means disposed between said spaced means and below and adjacent the outer pocketed face of said one run, said band-and-bobbin-guiding means having at least one bobbin-discharge opening formed therein for discharge of bobbins from said pockets on said

band, spaced means including at least two rotatable band-guiding elements engaging the inner surface of said band, and curved external band-and-bobbin-guiding means disposed adjacent said band in the zone of one of said rotatable guide elements, said curved band-and-bobbin-guiding means being movable toward and away from the axis of rotation of said one rotatable guide element to compensate for stretch or wear of said band, the axis of said one rotatable guide element being also movable for similar compensation, said first mentioned band-and-bobbin-guiding means and said curved band-and-bobbin-guiding means adjoining one another in a substantially unbroken line substantially tangential to the curvature of said curved band-and-bobbin-guiding means at the zone of juncture for smooth substantially continuous guiding of said band and bobbins and quills thereon during passage thereof along said one run and the outwardly convex curved portion of said band extending about said one rotatable guide element.

3. A transfer arrangement for bobbins, quills, or the like, comprising a flexible endless band having pockets formed in its outer surface for receiving and holding bobbins, quills, or the like, spaced means supporting said band at spaced apart positions to form at least two runs of said band, one of said runs being below another of said runs and band-and-bobbin-guiding means disposed between said spaced means and below and adjacent the outer pocketed face of said one run, said band-and-bobbin-guiding means having at least one bobbin-discharge opening formed therein for discharge of bobbins from said pockets on said band, and endless idler apron, being driven solely by surface engagement with the outer surface of said band and being retarded so as to aid in surface cleaning of said band by slippage between said band and said apron, said band being guided through an angle which is greater than 180° as measured internally of said band, the outer surface of said band facing downwardly in the zone of said angle and in the runs of said band forming said angle, said apron engaging with and guiding said band along a portion of each of said runs forming said angle.

4. A bobbin aligning and transfer arrangement comprising bobbin supply means, a first bobbin conveyor in bobbin receiving relation to said supply means, a second endless bobbin conveyor in bobbin receiving relation to said first conveyor, said second conveyor having transversely extending pockets formed thereon, means for removing and reorienting improperly oriented bobbins received by said second conveyor, said second conveyor including at least one downwardly facing bobbin discharge run, guide means disposed adjacent said second conveyor along said one discharge run and having a plurality of bobbin-discharge openings formed along and beneath said one run, means for selectively discharging bobbins through any one of said openings, said second conveyor having a first upwardly inclined run disposed in receiving relation to said first conveyor, and a further lengthwise extending upwardly facing transport run between said first run and said downwardly facing discharge run, and a further downwardly inclined return run connecting between said

5 discharge run and said first upwardly inclined receiving run, said discharge run and said return run forming an angle which is less than 180° as measured externally, and a movable endless band guide means engaging and guiding said second conveyor along the zone of intersection of said discharge run and said downwardly inclined return run of said second conveyor.

10 5. A transfer arrangement according to claim 4 wherein said first mentioned band-and-bobbin-guiding means and said curved band-and-bobbin-guiding means are joined by a substantially surface-smooth tongue and groove adjustment connection for smooth guidance of said band and bobbins carried thereby in any of its adjusted positions.

15 6. A bobbin aligning and transfer arrangement according to claim 4 wherein said movable endless band guide means comprises an endless idler apron engaging flush with both of said one downwardly facing discharge run and said downwardly inclined return run of said second conveyor as well as the intersection angle portion of said discharge run and said return run, said idler apron being driven solely by surface engagement with the outer surface of said second conveyor so as to aid in surface cleaning of said second conveyor by slippage between said second conveyor and said apron.

20 25 7. A bobbin aligning and transfer arrangement comprising: a bobbin supply means, an endless conveyor having a first run in bobbin receiving relation to said supply means, bobbin reversing means operably associated with said first run to remove and reorient improperly oriented bobbins, said endless conveyor having a second run receiving bobbins from said first run, said second run including a downwardly facing bobbin discharge portion, said endless conveyor having transversely extending pockets formed thereon, first guide means disposed adjacent said conveyor along said downwardly facing bobbin discharge portion and having at least one bobbin discharge opening formed along and beneath said discharge portion, means for selectively discharging bobbins through said discharge opening, and second guide means operably associated with said discharge portion to prevent the bobbins that are not discharged through said discharge opening from falling out of said transversely extending pockets and return such bobbins to said first run properly oriented whereby said bobbins are not acted upon by said bobbin reversing means.
